UNITED STATES PATENT OFFICE.

SLAUGHTER W. HUFF, OF BROOKLYN, NEW YORK.

SAFETY ELECTRIC FUSE.

1,188,786.

Specification of Letters Patent. Patented June 27, 1916.

Application filed April 27, 1914. Serial No. 834,754.

To all whom it may concern:

Be it known that I, SLAUGHTER W. HUFF, a citizen of the United States of America, and resident of Brooklyn, in the county of 5 Kings and State of New York, have invented certain new and useful Improvements in Safety Electric Fuses, of which the following is a specification.

This invention relates to fuses to be introduced into an electric circuit and embodying a conducting body that will fuse and interrupt a dangerous current to prevent the latter from injuring machinery which is being fed thereby; and particularly to that class of such fuses which embody a protecting housing or casing to confine the molten metal and gases therefrom and prevent damage at the time the fuse is blown.

More specifically, the present invention relates to that type of inclosed fuses which employ knife blade terminals extending within the casing to receive the fusible link or conductor, and extending beyond the 25 casing for connection with any form of support usually found upon the switch board; and the invention has for its object to provide for the assembly of the knife blade terminals with the fuse casing, in a manner that will not only provide an improved construction, but which will be very much more economical in material consumed in manufacture and time required for preparation of the parts and for assembling.

In carrying out the invention, the knife blades have formed upon them, or are otherwise provided with spurs or projections which are caused to embed themselves in the inner walls of the casing. Preferably, the 40 introduction of the knife blades takes place after they are assembled with the fusible link, so that the conducting parts can thus be assembled to the best advantage, and they are brought to position by introducing the 45 assembled conducting parts endwise through the casing; but the invention is not limited to this particular method of procedure. Preferably also, the breadth of the knife blades corresponds substantially with the diameter of the casing and the casing is first 50 distorted to enlarge its diameter in one direction and while the knife blades are being inserted, and sufficiently to freely admit the knife blades with their spurs, after which 55 the casing is restored to approximately its original form in a manner to cause the spurs

to embed themselves into the material of the casing. But the invention is not limited to this precise procedure, for I desire it to be understood that the breadth of the knife 60 blades may be greater than the original diameter of the casing, so that the latter will not be wholly restored from its first distortion, but may be caused to envelop the locking spurs with but a partial return movement. Or the original diameter of the casing may be sufficient without distortion to admit the knife blades with the spurs, and the embedding of the spurs in the material 65 of the casing may be developed by permanently reducing the diameter of the casing and retaining it in such distorted form, the essential feature being the interlock of the blade with the tubular casing by embedding the connecting spur, as distinguished from 70 introducing a stud through the casing wall into the blade, or introducing into a previously prepared opening in the wall, a projection integral with or otherwise carried on the blade; and the advantages, aside from 75 economy of production, being accuracy of position of the blades relatively to the fusible link, rigidity of grip upon the blades, and unimpairment of the hermetic walls. In every instance, suitable end caps are preferably applied over the ends of the casing 80 to retain the form of the casing and its assembled relation with the knife blades.

The invention will be fully understood upon reference to the accompanying drawings, in which—

Figure 1 is a transverse section, and Figs. 2 and 3 two longitudinal sections in planes at right angles to each other, of a fuse embodying the present invention; Figs. 4 and 5 95 are views suggesting the application of pressure for the purpose of effecting a first distortion sufficient to admit the knife blades, and a second or restoring distortion to embed the spurs and interlock the knife blades 100 with the casing; Figs. 6, 7 and 8 are detail views suggesting the application of dies for the purpose of swaging or upsetting the edges of the knife blades to form the locking projections or spurs; Fig. 9 is a detail 105 view suggesting a multiplicity of interlocking spurs that may be provided, instead of a single spur on each side of a blade.

1 represents a casing which is commonly made of fiber tubing, and 2 represents caps 110 such as are usually employed in the type of fuse to which the invention relates. 3 are the

knife blades which pass through slots in the caps 2 and are connected at their inner ends with fusible metal 4, either in the form of a plurality of wires, or in some other form 5 that may be desired.

It is customary to fill the casing of a fuse of this type with some inert matter that will largely fill the air space and completely embed the parts within the casing; hence, 10 there are several steps in the manufacture to be carried out after the knife blades are introduced and before the fuse casing is finally closed. For this reason, it is desirable to have some means for holding the knife 15 blades in place independently of the caps to avoid injury to the delicate fuse metal, which connects the knife blades, instead of leaving the knife blades free, as in cases where the cap and the knife blades 20 are secured in position by the same screws passing through the cap and intermediate wall and into the knife blades. On the other hand, it is a source of additional expense for material to use separate screws or any screws 25 at all for holding the knife blades in the casing, and an expense in time to have to drill and thread holes in the knife blades and then locate them relatively to the holes in the casing and insert the small screws that 30 must be employed, or to employ other forms of studs or projections that require registering with prepared openings in the casing. For these reasons, the present invention employs 35 projections 5 on the knife blades 3, which automatically embed themselves and, therefore, automatically locate the points at which they enter into engagement with the inner walls of the casing 1. This interengagement is accomplished by constructing the projections 40 in the form of spurs which are adapted to embed themselves into the material of the casing when the walls are pressed firmly against the spurs. This is conveniently accomplished in different ways. One method 45 is suggested in Figs. 4 and 5, according to which the breadth of the knife blades is approximately the same as the normal diameter of the casing, but is pressed between a pair of dies 6 until its diameter is elongated sufficiently to receive the knife blade with its 50 spurs, after which the pressure may be relieved in that direction, and then applied in a direction perpendicular thereto to press the walls firmly upon the spurs, by dies 6, as suggested in Fig. 5. A second pressing step may, of course, be omitted if desired 55 and the inherent resiliency of the casing be

relied upon to develop sufficient embedding or biting into the walls to prevent displacement of the knife blades. This gripping effect, by the resiliency of the casing, will assist in holding the knife blades while the casing is being shifted from the position of Fig. 4 to the position of Fig. 5.

After the knife blades are assembled with the casing and the necessary filler has been introduced, the caps 2 are put in place and secured in any suitable manner, as for instance by screws entering holes that may be drilled after assembly, or by cementing, or 70 by merely forcing a tightly fitting cap over the end of the tube, and when so applied the caps coöperate with the embedded spurs or interlocked projections to develop transverse rigidity in the knife blades. 75

As suggested in Fig. 9, any desired number of spurs may be formed on the knife blades.

The knife blades with any desired form of projection thereon may be cast, stamped, or otherwise formed, but I prefer to use standard stock of strip brass or copper cut to lengths and to form the spurs thereon by swaging or upsetting between dies 7, as suggested in Figs. 6, 7 and 8. 85

As already suggested, the invention may be measurably realized by interlocking the knife blade with the casing through means of a bayonet joint groove 8 (Fig. 10) receiving the lug or projection 5. 90

I claim:

1. In a safety electric fuse, a tubular casing, a knife blade terminal piece having a breadth corresponding substantially to a diameter of the tubular casing, and self-embedding spurs carried by the terminal piece and embedded in but not penetrating through the walls of the casing. 95
2. In a safety electric fuse, a tubular casing, a knife blade terminal piece having a breadth corresponding substantially to a diameter of the tubular casing, and self-embedding spurs carried by the terminal piece and penetrated into but not through the walls of the casing, and a band or hoop surrounding the casing and overlying the portions of the walls which the spurs penetrate. 100

The foregoing specification signed at Brooklyn, New York, this 6th day of April, 1914.

SLAUGHTER W. HUFF.

In presence of—

L. E. COLWELL,
JOHN A. THAKE.
